UNITED STATES PATENT OFFICE.

HOWARD M. DUDLEY, OF PHILADELPHIA, PENNSYLVANIA.

HOSIERY-DYEING MACHINE.

1,330,246.

Specification of Letters Patent. Patented Feb. 10, 1920.

Application filed July 19, 1918. Serial No. 245,632.

To all whom it may concern:

Be it known that I, HOWARD M. DUDLEY, a citizen of the United States, residing in the city of Philadelphia, county of Philadelphia, and State of Pennsylvania, have invented certain new and useful Improvements in Hosiery-Dyeing Machines, of which the following is a full, clear, and exact specification.

10 My invention relates to dyeing machines and refers particularly to machines suitable for the dyeing of hosiery.

The successful dyeing of hosiery and similar fabric forms is difficult on account 15 of the fact that the fabric masses are not uniform, and hence the dye liquor cannot be passed evenly and uniformly through all portions thereof. For this reason it is advisable to keep the hosiery in a more or less 20 loose condition within the dyeing liquid.

The generally employed method of simply passing the hosiery through the dyeing liquid is not successful because this motion does not bring all parts of the fabric 25 into uniform contact with the dyeing liquid, and hence the fabric is liable to be dyed unevenly.

I have overcome this difficulty by passing the dyeing liquid through the fabric in 30 reverse directions, while the fabric is being moved in the liquid, means being employed for the even and equal distribution of the liquid. By this means every portion of the fabric is subjected to uniform treatment 35 by the dyeing liquid and the results are therefore even and uniform.

In the drawings accompanying this application, and forming a part thereof, similar parts are designated by similar numerals.

Figure 1 is a broken vertical cross-section of one form of my device.

Fig. 2 is a section through the line 2—2 of Fig. 1.

45 Fig. 3 is a section through the line 3—3 of Fig. 1.

Fig. 4 is a broken vertical section showing the construction of the foraminous cover with its open position indicated in 50 dotted lines.

Fig. 5 is a top development of Fig. 4.

Fig. 6 is a vertical section of the testing device and its accompanying parts.

55 Fig. 7 is a section through the line 7—7 of Fig. 6.

The particular form of my device, as illustrated, comprises a receptacle formed by the sides 10 and 11, the ends 12 and 13, the hinged top 14 and the bottom 15.

An annular member 16 is supported by 60 the arms 17, 17, extending inwardly from the end 12. Annular members 18, 19 fixedly attached to the member 16 carry ball run-ways for the balls 20, 20.

An annular member 21 is supported by 65 the arms 22, 22 extending inwardly from the end 13. Annular members 23 and 24, fixedly attached to the member 21, carry run-ways for the balls 25, 25.

Within the receptacle is a revoluble dye- 70 ing device comprising a series of parallel spaced bars 26, 26 supported at their ends by the end members 27 and 28. The end member 28 carries the extended pointed cylindrical member 29 and the oppositely 75 extended pointed cylindrical member 30. The end member 27 carries the hollow conical member 31 which is extended into the hollow cylindrical member 32, the extended portion 33 of which forms a bushing with 80 the member 34 and the packing 35, revoluble around the pipe 36, carrying the valve 37, connected to a source of liquid supply. The pipe 36 is connected with the pipe 38, carrying the valve 39, connected with a 85 source of air supply. The end member 27 carries a series of arms 40, 40 which are integral with the annular members 41 and 42 which are fixedly attached to the annular members 43 and 44 respectively, having 90 run-ways for the balls 20, 20.

Within the space between the member 29 and the series of blades 26, 26, is a series of concentric tubular members 45, 45, the inner ends 46, 46 of which extend outwardly 95 to the blades 26, 26, thus forming a series of passages 48, 48 connecting the chamber 47 with the entire length of blades 26, 26 and the space between them.

A hollow conical member 50, forming a 100 chamber 51, with the member 30, is ex- tended into the hollow cylindrical member 52, which with the member 53 and the pack- ing 54 forms a stuffing box, revoluble around the pipe 55. The pipe 55, carrying the valve 56, is connected to a source of liquid supply and is connected with the pipe 57, carrying the valve 58, connected to a source of air supply. The member 50 is connected 105 to the member 30 by means of the bars 59, 110

59. A series of arms 60, 60 is connected to the flange member 61 of the member 50 and is integral with the annular members 62 and 63 which are attached to the annular members 64 and 65', having run-ways for the balls 25, 25.

Extended outwardly from the blades 26, 26 is a series of foraminous walls 66, 66, extended from the end 27 to the end 28 and 10 fixedly attached thereto.

Adjacent to the outer edge of each foraminous wall 66, is a rod 70 extending through the ends 27 and 28. Revoluble upon each rod 70 is a series of spaced sleeves 15 71, 71, to which is attached a series of parallel spaced rods 72, 72. The other end of each rod 72 has a recess 73 capable of placement over a rod 70. The rods 72, 72 of each series are connected together by the 20 connecting rod 74. Each of the exterior members of the series of rods 72, 72 carries a slidable plate 75, having openings 76 and 77 through which the screw bolts 78 and 79 pass and thread within the bar 72. Each 25 plate 75 has a recessed end 80, so arranged that when the plate 75 is pushed forward the end 80 will engage with the rod 70, and when the plate 75 is fixed in a non-slidable position by means of the bolts 78 and 79, 30 the series of rods 72, 72 will be locked to the rod 70. A handle 81 facilitates the movement of the plate 75.

By the above construction, a series of dyeing chambers are formed by the blades 26, 35 26, two foraminous walls 66, 66, the ends 27 and 28 and the series of rods 72, 72.

An imperforate wall 90, formed of two parts hinged at 91 and capable of being fixedly closed by means of a series of screw 40 bolts 92, fits tightly within the flange 93 of the member 27 and the flange 94 of the member 50, forming a tight joint therewith, packing 95 being introduced if necessary.

Attached to the inner face of the wall 90 45 is a series of baffle plates 96, 96.

Two cogged wheels 97 and 98, fixedly attached to the shaft 99, mesh with the cogged exteriors 100 and 101, of the members 41 and 62 respectively. The shaft 99 is connected to a source of revoluble power.

A drain pipe 104 carries the valve 105.

A pipe 152, carrying the valve 153, connects the pipe 36 with the supply tank and a pipe 154, carrying the valve 155, connects 55 the pipe 55 with the supply tank.

Abutting upon the end 27 is a testing device container composed of the sides 107, 108, 109 and the bottom 31. Removably carried by the testing device container is the 60 testing device comprised of the side members 110, 111, 112 and 113. Within these four side members is an abutment 114 upon which rests the foraminous plate 115 composed of a series of parallel spaced blades 65 116, 116. A removable wall 117 rests upon

the foraminous plate 115 and supports the foraminous plate 118 which is composed of a series of parallel spaced bars 119, 119. Capable of abutment upon the plate 118 is a top 120 carrying a series of baffle plates 70 121, 121.

The cover 122 is capable of abutment upon the top 120 and can be fixedly attached to the side members 110, 111, 112 and 113 by means of the screw bolts 123, 123. Fixedly 75 attached to the cover 122 is the bracket 124 carrying the shaft 125, upon which the arm 126 is pivotally carried. Pivotally attached to the arm 126 is the pin 127 slidable within the bearing 128. The pin 127 carries a 80 fixedly attached collar 129, a spiral spring 130 abutting upon the collar 129 and the bearing 128. The exterior end of the pin 127 is capable of insertion into and removal from the opening 131 in the side member 85 108. The arm 126 carries an opening 132 at its upper end in order that a hook 133 may be inserted for lifting the device. A series of nested cones 134, 134 are fixedly attached to the foraminous plate 115. An 90 opening 135 connects the chamber 136 and the larger device with the chamber 137 of the testing device. An opening 138 connects the chamber 139 with the lower portion of the testing device.

95 The operation of the testing device is as follows: the testing device being removed from the testing device container.—

The foraminous plate 114, the member 117, the foraminous plate 118 and the top 100 120 are introduced, the fabric being introduced between the two plates 115 and 118, the cover 122 is then placed upon the device and fixedly attached thereto by means of the screw bolts 123, 123. The hook 133 is then 105 inserted into the opening 132 of the arm 126 and the weight of the testing device will thus draw the bolt 127 inwardly. The testing device, while in this condition, is lowered into the testing device container, and 110 when in place, the removal of the weight of the testing device from the hook 133 will allow the bolt 127 to pass into the opening 131 and member 108, thus locking the testing device in position.

115 The operation of the device is as follows:—

The top 14 is opened and the revoluble member revolved until one of the dyeing chambers is uppermost. The hinged series 120 of rods 72, 72 is then revolved into the opened position, the hosiery introduced into the chamber and the rods 72, 72 closed and locked by means of the bolts 75, 75. This operation is conducted with each one of the 125 dyeing chambers. The imperforate cover 90 is then introduced into place and clamped by means of the screw bolts 92, 92 forming a tight joint with the flanges 93 and 94. The top 14 is then closed and clamped in a 130

closed position. All of the valves are closed with the exception of valves 37 and 155 and dye liquor is forced through the pipe 36 while the revoluble reel carrying the dyeing chambers is revolved by means of the cogged wheels 97 and 98. The dye liquor then passes through the pipe 36, the conical member 31 and the passages 48, 48 formed by the nested conical members 45, 45, the liquid passing outwardly between the parallel blades 26, 26 into the dyeing chambers containing the fabric, and thence outwardly through the spaced bars 72, 72 into the chamber 136, and thence through the chamber 51, the pipe 55 and the pipe 154.

When a reverse flow of the liquid is desired, valves 37 and 155 are closed and valves 56 and 153 are opened. The dye liquid then passes through pipe 55, chamber 51, is distributed by the baffle plates 96, 96 in chamber 136, passes inwardly between the rods 72, 72 into the dyeing chambers containing the fabric and thence between the spaced bars 26, 26 through the member 31 and the pipes 36 and 152 into the supply chamber. The liquid is thus given a continuous flow in reverse directions through the revoluble member carrying the dyeing chambers.

During the first described process of the flow of liquid, it also passes through the opening 138, through the testing device and the opening 135 into the chamber 136; whereas during the second described flow of the liquid, it passes through the chamber 136, through the opening 135, through the testing device and thence through the opening 138 into the chamber of the member 31.

When it is desired to pass air through the dyeing chambers, the air is passed through the pipes 38 or 57 respectively, the valves 37 and 56 being closed, and hence air passes in the direction of the flow of liquid as described above.

It will thus be seen that when the liquid passes inwardly through the pipe 36, it is distributed evenly and with equal pressure over the series of bars 26, 26 and into the dyeing chambers by means of the nested members 45, 45; and while it passes through the member 50, it is distributed evenly and with equal pressure over the series of blades 72, 72 and into the dyeing chambers by means of the baffle plates 96, 96, thus producing in both cases an even and equal flow through all of the dyeing chambers while the fabric is being moved therein by the revolution of the device.

I do not limit myself to the size, number, shape or arrangement of parts as described and shown, all of which may be varied without going beyond the scope of my invention as described and claimed.

What I claim is:—

1. In a dyeing machine, in combination, a series of dyeing chambers having imper-

forate ends and foraminous sides revoluble around a common axis, means for revolving the chambers, means for passing a liquid in reverse directions through the chambers during their revolution and means within the liquid passage whereby the liquid is impinged evenly upon the foraminous sides of the chambers.

2. In a dyeing machine, in combination, a series of dyeing chambers having imperforate ends and foraminous sides revoluble around a common axis, means for revolving the chambers, means for passing a liquid in reverse directions through the chambers during their revolution, means within the liquid passages whereby the liquid is impinged evenly upon the foraminous sides of the chambers and means for passing air in reverse directions through the chambers during their revolution.

3. In a dyeing machine, in combination, a series of dyeing chambers having imperforate ends and foraminous sides revoluble around a common axis of revolution, means for revolving the chambers, a series of hollow nested members connecting the interior sides of the dyeing chambers with a source of liquid supply, means connecting the exterior sides of the dyeing chambers with a source of liquid supply and means for passing a liquid through the dyeing chambers in reverse directions during the revolution.

4. In a dyeing machine, in combination, a series of dyeing chambers having imperforate ends and foraminous sides revoluble around a common axis of revolution, means for revolving the chambers, a series of hollow nested members connecting the interior sides of the dyeing chambers with a source of liquid supply, means connecting the exterior sides of the dyeing chambers with a source of liquid supply, a series of baffle plates exterior of the dyeing chambers with in the liquid passage and means for passing a liquid through the dyeing chambers in reverse directions during their revolution.

5. In a dyeing machine, in combination, a series of dyeing chambers having imperforate ends and foraminous sides revoluble around a common axis of revolution, means for revolving the chambers, a series of hollow nested members connecting the interior sides of the dyeing chambers with a source of liquid supply, means connecting the exterior sides of the dyeing chambers with a source of liquid supply, means for continuously passing a liquid in reverse directions through the dyeing chambers during their revolution and means for continuously passing air in reverse directions through the dyeing chambers during their revolution.

6. In a dyeing machine, in combination, a series of dyeing chambers having imperforate ends and foraminous sides revoluble around a common axis of revolution, means

- for revolving the chambers, a series of hollow nested members connecting the interior sides of the dyeing chambers with a source of liquid supply, means connecting the exterior sides of the dyeing chambers with a source of liquid supply, a series of baffle plates exterior of the dyeing chambers within the liquid passage, means for continuously passing a liquid in reverse directions through the dyeing chambers during their revolution and means for continuously passing air in reverse directions through the dyeing chambers during their revolution.
7. In a dyeing machine, in combination, a series of dyeing chambers having imperforate ends and foraminous sides revoluble around a common axis of revolution, means for revolving the chambers, a removable imperforate top for each chamber, a series of hollow nested members connecting the interior sides of the dyeing chambers with a source of liquid supply means connecting the exterior sides of the dyeing chambers with a

source of liquid supply and means for passing a liquid through the dyeing chambers in reverse directions during their revolution.

8. In a dyeing machine, in combination, a series of dyeing chambers having imperforate ends and foraminous sides revoluble around a common axis of revolution, means for revolving the chambers, a removable imperforate top for each chamber, a series of hollow nested members connecting the interior sides of the dyeing chambers with a source of liquid supply, means connecting the interior sides of the dyeing chambers with a source of liquid supply, a series of baffle plates exterior of the dyeing chambers within the liquid passage and means for passing a liquid through the dyeing chambers in reverse directions during their revolution.

Signed at New York, in the county of New York and State of New York this 15th day of July, 1918.

HOWARD M. DUDLEY.
